SUPPLEMENTAL AIR SUPPLY MECHANISM
FOR AUTOMOTIVE ENGINES

Frederick M. Laserson, Los Angeles, Calif.

Application February 25, 1949; Serial No. 78,358

32 Claims. (Cl. 192—096)

1

This invention relates to means for improving the air supply system for internal combustion engines such as are used in automotive vehicles.

It is an object of this invention to provide novel means for this purpose without the necessity of alteration in the design or in the adjustment of conventional types of engines or carburetors; and without employing any appreciable engine power to achieve the purpose.

It is another object of this invention to provide such means comprising a motor driven impeller incorporated in an air intake channel leading to the carburetor, the motor being wholly or partly within said channel, or adjacent thereto.

It is another object of this invention to provide a motor driven impeller between the air cleaner and the carburetor and incorporated wholly or partly in the air cleaner.

It is another object of this invention to provide means for improving the air supply systems of automotive engines which is controlled automatically in accordance with the operation of the engine.

It is another object of this invention to provide an improved means for the purpose described which is controlled in accordance with the opening and closing of the engine throttle.

It is another object of this invention to provide an improved means for supplying air to the air supply systems of automotive engines which is controlled automatically as a function of opening and closing of the engine throttle.

It is a further object of this invention to provide means for supplying air to the engine carburetor additionally to that normally passing to the carburetor, which means becomes inoperative responsive to release of the engine throttle so as not to interfere with or impair the operation of the engine at idling speeds.

It is another object of this invention to provide such means which is controlled as a function of the speed of the engine.

This invention possesses many other advantages and has other objects which may be made more easily apparent from a consideration of several embodiments of the invention. For this purpose there are shown several forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

2

In the accompanying drawings:

Figure 1 is an elevation, partly in section, showing one form of motor driven impeller, installed for use;

Figure 2 is a cross section taken substantially as indicated by line 2—2 of Figure 1;

Figure 3 is a vertical section, partly schematic, showing one of the motor controls;

Figure 4 is a similar view, showing another form of control;

Figure 5 is a cross section taken substantially as indicated by line 5—5 of Figure 4;

Figure 6 is a circuit diagram of electrical controls;

Figure 7 is a schematic view showing a modified form of motor control;

Figure 8 is a diagrammatic view showing a modified form of impeller motor;

Figure 9 is a view similar to Figure 1, but showing a modified form of the invention;

Figure 10 is a transverse section, taken substantially as indicated by line 10—10 of Figure 9;

Figure 11 is another view similar to Figure 1, but showing a further modified form of the invention;

Figure 12 is a transverse section, taken substantially as indicated by line 12—12 of Figure 11; and

Figure 13 is a view partly in section and largely schematic showing a throttle actuated air control.

Referring to the drawings, particularly Figures 1 and 2, a conventional air cleaner is indicated by the numeral 5 and has an axially extending outlet passage 6 connected with the air intake passage of a conventional down draft carburetor 8 by the aid of a channel forming member 9, the carburetor 8 supplying the explosive mixture for an internal combustion engine (not shown). The member 9 is fastened to the bottom of the air cleaner 5 as by screws 12, and is detachably secured to the air horn 13 of the carburetor 8 by the aid of a clamping band 14 in a well understood manner.

An air impeller 15 is provided in the air intake channel 16 formed by the member 9, being mounted on one end of the shaft 17 of an electric motor 18 vertically disposed in the air cleaner passage 10 and supported by the aid of a bracket 19. Means to be described presently, are provided for engaging the motor 18 in accordance with the operation of the engine and preferably from the electrical system commonly provided with such an engine. Further, brake means 20 are provided for restraining rotation of the impeller 15 when the motor 18 is deenergized.

Referring to Figures 2, it will be seen that the member 9 has a side extension or housing 21 providing a pair of spaced walls 21-a and 21-b slidably mounting a brake member 24 of magnetic material urged to engage the flange 15-a of the impeller 15 by a compression spring 25 confined between the inner wall 21-b and a flange 24-a on the member 24. An electromagnet 26 is mounted in the housing 21 adjacent the member 24, and when energized attracts the brake member 24 with sufficient force to overcome the spring 25 so that the impeller 15 is released. The magnet 26 is connected for simultaneous energization with the motor 18, thus, when the motor 18 is energized the brake member 24 is released and when the motor is deenergized the member 24 reengages responsive to spring 25 which exerts sufficient force to cause the impeller 15 to stop substantially immediately.

It is desirable that the amount of air delivered by the impeller 15 to the carburetor, in addition to that normally drawn by the vacuum of the engine be a function of the operating conditions of the engine with which the system is associated. Thus, at high speeds, it is generally desirable that a greater amount of air be delivered to the carburetor than under idling or light load conditions. Means are therefore provided to control the volume of extra air to the best advantage of the engine. Such means may take innumerable forms and be subject to various combinations and arrangements, as will suggest themselves from the preceding and following examples.

As shown in Figure 6, the motor 18 is arranged to be energized by means of a source of electrical energy 30 which may comprise the usual storage battery 31 and generator 32 of an automotive vehicle. One side of the battery and generator are connected to a common ground such as the vehicle frame the other sides being connected by a lead 33 from which a lead 34 is connected to one side of the motor 18. A conventional manually operated rheostat 35, including a switch 35-a, is incorporated in the lead 34 for optionally controlling operation of the motor 18 in conjunction with certain automatic means now to be described. Thus, a second switch 37, interposed in lead 34 serves to prevent energization of the motor 18 upon actuation of the clutch mechanism commonly provided with automobile engines and the like, to disconnect the engine from driving relation with the vehicle or other load.

As is well understood such mechanism is usually spring urged into load driving relation and includes a pivoted lever or pedal 38 for opposing the spring and actuating the mechanism to disconnect the load. Referring to Figure 4, the pedal 38 is urged counterclockwise to the limiting position shown when the clutch is allowed to engage, and is swung clockwise by suitable pressure when the clutch is disengaged.

An insulation block 39 is mounted beneath the floor board 40 and has a pair of contact members 41 and 42 respectively secured on opposite sides thereof, adapted to be bridged by the upturned end portion 43-a of a conducting arm 43 pivoted on the block 39 by the aid of a pin 44 for movement between positions in which the end 43-a is between and closes said contacts and in which it is withdrawn and opens the contacts. A compression spring 45 urges the arm 43 to open the contacts, a screw 46 serving

to appropriately limit such movement. An insulation block 47 is provided on arm 43 to engage the lever 38, as the lever 38 nears the limit of its travel in load connecting direction so that its final movement as the load is connected will cause the lever 43 to close the contacts 41 and 42. Conversely, when the lever 38 is swung clockwise to disconnect the load, the lever 43 will be freed to move away from the contacts 41 and 42 under the influence of the spring 45 and open the contacts. Supplemental means including a variable resistance 50 and switch means 51 responsive to various operating conditions of the engine, such as the throttle opening or the speed of the engine or associated mechanism may be provided in the motor control circuit.

Referring to Figure 3, a pedal 55 pivotally mounted on the upper side of a floor board 56 is arranged to operate a member 57 pivotally mounted below the floor board 56 and connected at one end as 57-a to the throttle (not shown) usually provided for controlling an engine of the type under consideration, by the aid of linkage 58. A tension spring 59, shown by way of example as connected to the member 57 adjacent one end thereof, serves to urge the throttle toward closed position and against a suitable stop (not shown) which maintains the throttle sufficiently open to permit the engine to operate at idling speed. Such movement of the lever 57 in throttle closing direction moves the pedal 55 upwardly from the floor 56, appropriate pressure on the pedal 55 serving to move the parts 35 in the opposite direction against the force of the spring 59 and open throttle.

A tubular element 60 of suitable metal or other conducting material is pivotally mounted on the end 57-b of the member 57 opposite the linkage 58 by the aid of a pin 61 secured on the exterior of the tube 60. The lower end of the tube 60 is closed by a long plug 62 of insulating material which mounts a contact 63 having a shank 64 projecting from the tube 60 for connection with a lead 65. The upper end of the tube 60 has a plunger 66 of conducting material slidably therein, and in good conducting relation therewith. The plunger 66 has a reduced portion 66-a which extends from the tube 60 through a bushing 67 and is urged outwardly by a compression spring 68, a collar 69 on the plunger 66 limiting such outward movement. The outer end of the plunger 66 is formed as a ball 66-b engaging a suitable socket 65-a in the pedal 55, the inner end of the plunger forming a contact 72 adapted to engage the contact 63 which contacts cooperate to form the switch 51. Contact 72 is normally maintained in spaced relation with contact 63 by the spring 68. When the contacts 63, 72 are closed, contact 63 is grounded by contact 72, plunger 66, tube 60 and the throttle linkage 57, 58. The arrangement is such that spring 59 exerts a greater force opposing movement of the tube 60 in throttle opening direction than can be exerted by the spring 68. Thus, whenever pedal 55 is depressed to open the throttle, contacts 63, 72 are closed causing energization of the motor 18 and brake release coil 26 and operation of the impeller 15. When the pedal 55 is released to allow the engine to idle, the contacts 63, 72 open, deenergizing the motor 18.

To vary the speed of the motor 18 in accordance with the throttle opening, the resistor 74 is provided, being mounted in a protective casing 75 of insulating material by the aid of a

through bolt 76 passing through the resistor 14 and engaging the heads 75-a and 75-b at the opposite ends of the casing 75. The resistor 14 is shown by way of example as a wire wound resistor with the turns of wire forming respectively contacts providing progressively varying values of resistance. The upper end of the resistor 14 is connected by lead 77 to the bolt 76, the projecting end of which serves as a binding post to which the lead 85 is connected.

A contact arm 78 cooperates with the resistor 14 to form the rheostat 50 and has a conducting roller 79 which extends through a slot 75-c in the wall of the casing 75 and engages the resistor contacts. The roller 79 is appropriately insulated from the arm 78 and is connected to the motor 18 by a lead 80. The arm 78 is pivotally mounted at 81 in a bracket 82 secured beneath the floor board 56, and has an angled extension 78-a against which a spring 83 is confined for urging the arm 78 upwardly about its pivot to maintain the roller 79 in contact with the resistor 14.

When the pedal 55, tube 60, resistor 14, etc., are in their uppermost position corresponding with minimum throttle opening, the roller 79 engages the lower end portion of the resistor 14 providing maximum resistance. As the pedal 55, tube 60, resistor 14, etc., are moved downwardly to increase the throttle opening, the resistor 14 moves correspondingly with respect to the roller 79 to progressively reduce the portion of the resistance in the circuit, and thus vary the motor speed and with it the amount of air supplied additionally by the impeller to the carburetor.

If desired, the speed of the motor 18 and impeller 15 may be made to vary as a function of the speed of the engine or of some moving part of the vehicle. One form of mechanism for this purpose is shown in Figure 7 and comprises a frame 90 rotatably mounting a shaft 91 carrying a pulley 92 at one end adapted to be connected in driving relation with the desired part, as by the aid of a belt 93. The shaft 91 has a conventional fly-ball governor 94 mounted thereon comprising a collar 95 fixed on the shaft and a sleeve 96 axially slidably on the shaft. Pairs of arms 97 and 98 pivotally joined at one end are connected respectively at their other ends to the collar 95 and sleeve 96, and carry weights 99 at their connected ends. As the shaft 91 rotates, the weights tend to move outwardly due to centrifugal force, urging sleeve 96 to approach collar 95, in a well understood manner. A contact arm 100 is mounted on sleeve 96 to move axially therewith while permitting free rotation thereof, and has a downward extension 100-a slidably engaging a guide bar 101. A compression spring 102 on the bar 101 is adjustably confined against the extension 100-a by a nut 103 and urges the sleeve 96 away from the collar 95 in opposition to the force created by the weights 99. Above the shaft 91 is a resistor 104 similar to the previously discussed resistor 14 and adapted to be engaged by a conducting roller 105 carried by the upper end of arm 100. The arrangement is such that the roller 105 does not contact the resistor 104 until shaft 91 reaches a predetermined minimum speed, thus serving as a switch. Thereafter, further increase in speed causes the roller 105 to advance along the resistor 104 toward the lead 107, which may correspond with the lead 29 of the previously described form, progressively reducing the resistance in the motor circuit and causing the speed of the motor 18 to increase. The roller 105 is connected to ground as by the

aid of lead 106. Reduction in the speed of shaft 91 will allow the contact roller 105 to move in the opposite direction in response to spring 102, increasing the resistance in the motor circuit and reducing the speed of the motor 18, and eventually opening the contact with the resistor 104, stopping the motor. By appropriate adjustments, this contact opening may be caused to occur at engine idling speed.

If desired, a motor having a split field winding may be substituted for the motor 18 and the rheostat 50. A motor 109 of this type is shown diagrammatically in Figure 8 and comprises a pair of field windings 110 and 111, each formed in two sections 110-a and 110-b, 111-a and 111-b respectively. The control switch therefor comprises a stationary plate 112 having angularly spaced contacts 113 and 114 and 115 connected respectively to one side of the power circuit and to winding sections 110-a and 110-b, and diametrically opposite contacts 116, 117 and 118 connected respectively to the other side of the power circuit and to winding sections 111-a and 111-b. The switch has a movable member 119 with a pair of conducting segments 120 and 121 adapted optionally to connect one or both sections of the windings in the power circuit.

In the position of the switch shown in Figure 8, the motor 109 is deenergized. Appropriate 30 counterclockwise movement of switch member 119 will cause segment 120 to close contacts 113 and 114, and segment 121 to close contacts 116 and 117. Thus, current will flow from one power lead through winding section 110-a to the motor 35 armature, thence through winding section 111-a to the other power lead, and the motor will operate at reduced speed. Further movement of the switch member will cause the segment 120 to engage additionally the contact 115, and the segment 121 to engage additionally the contacts 118. Current can then flow through the entire 40 windings 110 and 111, and the motor will operate at full speed.

The switch member 119 may be arranged to be 45 operated in accordance with the throttle opening or as a function of the engine speed, for which purpose it is shown as provided with an operating arm 122 adapted to be connected as by the aid of a link 123 with the foot pedal 55 (Figure 3) in lieu of the mechanism shown therein or with arm 100 (Figure 7) in lieu of the variable resistance arrangement 104, 106.

It is not necessary that the impeller driving motor be located in the air cleaner. Thus, in 55 Figure 9, a fragment of an air cleaner 125 having a lateral air outlet is shown, connected by a horizontal channel forming member 126 with the carburetor 127. The impeller driving motor 128 and the impeller 129 are both mounted in the air channel. An automatic brake 130 is provided as before (Figure 10).

In Figures 9 and 10 a throttle actuated air control is shown at 140 which is automatic and controlled by the opening and closing of the throttle valve. This air control 140 comprises an opening 141 in the wall of the air channel forming member 126, and having a disc closure 142 slidable on a rod 143 extending through the opening 141 and supported by cross bar 144. A spring 145 urges the disc 142 to closing position, being adjustably confined against the disc as by a knurled nut 146 threaded on the rod 143. The arrangement is such that when the pressure of the air delivered by the impeller 129 reaches a 70 predetermined amount, the closure 142 is un-

seated, allowing air to escape and reducing the pressure.

In Figures 11 and 12, a fragment of an air cleaner 131 similar to that of Figure 1 is shown, the air outlet thereof being connected by a vertical channel forming member 132 with the carburetor 133. The member 132 has a semi-circular enlargement 132-a on one side for accommodating the impeller 134, and a circular flanged opening 135 in which the motor 136 is mounted, the motor 136 thus being partly within the air channel. Automatic brake means 137 for checking rotation of the impeller 134, responsive to closing of the engine throttle, are provided. This brake 137 comprises an arm 151, rockably mounted within the air channel by the aid of a shaft 158 extending through the wall of the member 132 and carrying a brake shoe 159 adapted to engage the periphery of the impeller 134. A lever 160 is fixed on the outer end of shaft 158 and is connected with an arm 162 provided on the engine throttle 163 by a lost motion connection including a link 161 having a slot 161-a engaged by a pin 162-a on arm 162. The engine throttle 163 is provided with conventional operating means (not shown). The arrangement is such that when the throttle 163 is open the weight of the brake shoe 159 and arm 157 urge the shoe 159 out of engagement with the impeller 134, such movement being limited by contact of lever 160 with a stop pin 164. As the throttle 163 approaches closed position, pin 162-a engages the lower end of slot 161-a and applies the brake. Opening of the throttle 163 releases the brake, and it will be readily apparent that movement of the throttle 163 except as it reaches or leaves closed position will not affect the brake, pin 162-a sliding freely in slot 161-a.

In Figure 13 an air control 150 is shown which is linked to the throttle valve so as to be positively controlled by the opening and closing thereof. An opening 151 in the wall of the air channel forming member is provided with a butterfly closure 152 having an operating arm 153 connected to an arm 154 provided on the engine throttle 155 which has conventional operating means (not shown). The arms 153 and 154 are connected for simultaneous movement by a link 156, the arms being so directed and proportioned that opening movement of the throttle 155 causes closing movement of the closure 152 to a desired extent, and vice versa.

I claim:

1. In an air supply system for the internal combustion engine of an operative motor vehicle including a carburetor having an air intake channel: means including an impeller mounted in said channel for providing an additional supply of air to that normally passing to the carburetor; an electric motor for driving said impeller; and means responsive to an operating condition of said motor vehicle for controlling said additional supply of air.

2. In an air supply system for an automobile internal combustion engine including a carburetor; means including an impeller for providing an additional supply of air to that normally passing to the carburetor; an electric motor for driving said impeller; and control means including switch and brake mechanism.

3. In an air supply system for an automobile internal combustion engine including a carburetor: means including an impeller for providing an additional supply of air to that normally passing to the carburetor; an electric motor for driv-

ing said impeller; switch means for said motor; brake mechanism for said impeller; and operating means for said brake mechanism.

4. In an air supply system for an automobile internal combustion engine including a carburetor, and means forming an air intake channel to said carburetor: an air impeller in said channel for forcing into the normal air-gasoline mixture of the carburetor air in excess of that normally obtainable by the carburetor from the atmosphere; and an electric motor for driving said impeller.

5. In an air supply system for an automobile internal combustion engine, including a carburetor and an air cleaner having an air passage to said carburetor; means for providing an additional supply of air to that normally passing to the carburetor, comprising an impeller in said passage and an electric driving motor therefor.

6. In an air supply system for an automobile internal combustion engine, including a carburetor and means forming an air intake channel therefor: an impeller in said channel for providing an additional supply of air to that normally passing to the carburetor; a motor for driving said impeller; and means for controlling the supply of air delivered by the impeller, including a friction brake for quickly reducing the speed of the impeller.

7. In an air supply system for an automobile internal combustion engine, including a carburetor and an air cleaner channel: an impeller in said channel for providing an additional supply of air to that normally passing to the carburetor; an electric motor for driving said impeller; and means including electroresponsive means for controlling said motor.

8. In an air supply system for an automobile internal combustion engine, including a carburetor; a throttle controlling said engine; means for operating said throttle; means including an impeller, for providing an additional supply of air to that normally passing to said carburetor; a motor for driving said impeller; means controlling said motor including a switch and a variable resistance; and means whereby initial movement of said throttle operating means in throttle opening direction closes said switch, movement thereafter reduces said resistance, and release of the throttle operating means opens said switch.

9. In an air supply system for an automobile internal combustion engine, including a carburetor: an impeller for providing an additional supply of air to that normally passing to said carburetor; an electric motor for driving said impeller; and means controlling said motor as a function of the engine speed.

10. In an air supply system for an automobile internal combustion engine, including a carburetor, means forming an air intake channel to said carburetor, and a throttle for controlling said engine: means including an impeller, for providing an additional supply of air to that normally passing to said carburetor, and valve means controlling said additional supply of air in accordance with the opening and closing of said throttle, comprising a spring pressed closure responsive to variation in air pressure in said channel to open and to close.

11. In an air supply system for an automobile internal combustion engine, including a carburetor, means forming an air intake channel to said carburetor, and a throttle for controlling said engine: means including an impeller, for

providing an additional supply of air to that normally passing to said carburetor, and valve means controlling said additional supply of air in accordance with the opening and closing of said throttle, comprising a closure, and means forming a mechanical connection between said closure and said throttle to cause opening movement of said closure in response to closing of said throttle and closing movement of said closure in response to opening movement of said throttle.

12. In an air supplying system for an automobile internal combustion engine, including a carburetor: means for optionally connecting said engine in driving relation with a load; means including an impeller for providing an additional supply of air to that normally passing to said carburetor; a motor for driving said impeller; and means responsive to disconnection of said load for deenergizing said motor.

13. In an air supply system for an automobile internal combustion engine, including a carburetor and means forming an air intake channel therefor: an impeller for providing an additional supply of air to that normally passing to said carburetor; an electric motor for driving said impeller; switch means for controlling said motor; and brake means for restraining rotation of said impeller responsive to the switch means.

14. In an air supply system for an automobile internal combustion engine, including a carburetor and means forming an air intake channel therefor: an impeller for providing an additional supply of air to that normally passing to said carburetor; an electric motor for driving said impeller; switch means controlling said motor; normally engaged brake means restraining rotation of said impeller; and electro-magnetic means for releasing said brake means, operated in response to energization of said motor.

15. In an air supply system for an automobile internal combustion engine, including a carburetor: means including a movable member for optionally connecting said engine in driving relation with a load; means including an impeller for providing an additional supply of air to that normally passing to said carburetor; a motor for driving said impeller; optionally operable switch means for connecting said motor with a source of current; and means operated by movement of said member to disconnect said load, to disconnect said motor from said source.

16. In an air supply system for an automobile internal combustion engine, including a carburetor: means for optionally connecting said engine in driving relation with a load; means including an impeller for providing an additional supply of air to that normally passing to said carburetor; an electric motor for driving said impeller; means responsive to the operating conditions of said engine for controlling said motor; and means responsive to disconnection of said load, causing deenergization of said motor.

17. In an air supply system for an automobile internal combustion engine, including a carburetor: means for optionally connecting said engine in driving relation with a load; means including an impeller for providing an additional supply of air to that normally passing to said carburetor; an electric motor for driving said impeller; means controlling said motor as a function of the engine speed; and means responsive to disconnection of said load, causing deenergization of the motor.

18. In an air supply system for an automobile internal combustion engine including a generator

having means forming an air channel for supplying air thereto; a throttle for controlling said engine; means including an impeller in said channel for providing an additional supply of air to that normally passing to said carburetor; an electric motor for driving said impeller; and switch means shutting off said motor responsive to the closing of said throttle to an idling position.

19. In an air supply system for an automobile internal combustion engine, including a carburetor: a throttle for controlling said engine; means for operating said throttle, including a pivoted arm; means for optionally connecting said engine in driving relation with a load, including a pivoted arm; means including an impeller for moving air to said carburetor; an electric motor for driving said impeller; and means, including a switch, operated by each of said arms for cooperatively controlling said motor in accordance with the throttle opening and the connection of said load with the engine.

20. In an air supply system for an automobile internal combustion engine, including a carburetor: a throttle for controlling said engine; means for operating said throttle; means, including a movable member, for optionally connecting said engine in driving relation with a load; means including an impeller for moving air to said carburetor; an electric motor for driving said impeller; a normally engaged brake restraining rotation of said impeller; means for releasing said brake upon energization of said motor; means for controlling said motor in accordance with the throttle opening, operated by the throttle operating means.

21. In an air supply system for an automobile internal combustion engine, including a carburetor: means, including a movable member, for optionally connecting said engine in driving relation with a load; means including an impeller; for moving air to said carburetor; an electric motor for driving said impeller; friction brake restraining rotation of said impeller; means for releasing said brake upon energization of said motor; means for controlling said motor in accordance with the speed of the engine; and switch means operated by said movable member for deenergizing said motor upon disconnection of said load from the engine.

22. In an air supply system for an internal combustion engine, including a carburetor: means including an impeller for providing an additional supply of air to that normally passing to said carburetor; and a speed responsive circuit controller for controlling said motor, comprising: a rotatable shaft adapted to be driven in accordance with the speed to which response is desired; a fly ball governor mounted on said shaft to rotate therewith including an axially slid able sleeve; a contact arm rotatably engaging said sleeve, and restrained against rotation to move axially with the sleeve; and a resistance having spaced contact forming means connected to progressively varying portions of said resistance and adapted to be respectively contacted by said arm.

23. In a circuit-controller: an elongated guide member having a switch contact therein; an element slid able in said guide and having a co-operating contact; a pressure member for urging said contact element inwardly of said guide to close the contacts; means resiliently opposing inward movement of said element; means mounting said guide member for movement in a generally longitudinal direction; means resiliently

opposing movement of said member to cause said contacts to close; a resistance mounted for movement with said guide member, connected to one of said contacts, and having spaced contact forming means connected to progressively varying portions of said resistance; and a contact arm adapted to respectively engage said contacts upon movement of said resistance.

24. In an air supply system for an automotive vehicle engine, including a carburetor, an air cleaner, and means forming an air intake channel between said air cleaner and said carburetor, said vehicle including a source of electrical energy; an impeller for moving air through said channel; an electric motor for driving said impeller; a normally engaged brake restraining rotation of said impeller; electrically actuated means for releasing said brake; and means connecting said motor and said actuating means for substantially simultaneous energization by said source.

25. In an air supply system for an automobile internal combustion engine including a carburetor; a throttle for controlling said engine; means including an impeller for providing an additional supply of air to that normally passing to the carburetor; an electric motor for driving said impeller; and brake mechanism operated in accordance with the position of said throttle for restraining rotation of said impeller.

26. In an air supply system for an automobile internal combustion engine including a carburetor; a throttle for controlling said engine; means including an impeller for providing an additional supply of air to that normally passing to the carburetor; an electric motor for driving said impeller; brake mechanism for restraining rotation of said impeller, including a rockable member; and means forming a lost motion connection between said throttle and said member whereby movement of said throttle to closed position actuates said brake mechanism.

27. In an air supply system for the internal combustion engine of an operative motor vehicle, including a carburetor having an air intake channel, an impeller mounted in said channel for forcing an additional amount of air into the carburetor to that normally passing to the carburetor, means for rotating the impeller, and means for stopping the rotation of said impeller actuated by an operating control of said vehicle.

28. In an air supply system for the internal combustion engine of a motor vehicle including a carburetor having an air intake channel, an impeller in said channel for forcing an additional supply of air into the carburetor to that normally passing to the carburetor, an electric motor for rotating said impeller, and an electric switch for starting and stopping said motor actuated by and operating control of the motor vehicle.

29. In an air supply system for the internal

combustion engine of a motor vehicle including a carburetor having an air intake channel, an impeller in said channel for forcing an additional supply of air into the carburetor to that normally passing to the carburetor, an electric motor for driving said impeller, an electric switch for starting said motor responsive to an operating control of said motor vehicle and for stopping said motor responsive to another operational control of the motor vehicle, and means for varying the speed of said electric motor responsive to varying conditions of operation of said motor vehicle between said first two conditions of operational controls.

30. In an air supply system for the internal combustion engine of a motor vehicle, including a carburetor, a throttle controlling the engine, and means for operating the throttle including means urging the throttle to a position causing the engine to idle; means including an impeller for providing an additional supply of air to that normally passing to the carburetor, and means associated with said throttle operating means for stopping the operation of said impeller incident to release of said throttle operating means.

31. In an air supply system for the internal combustion engine of a motor vehicle, including a carburetor, a throttle controlling the engine, and means for operating the throttle including means urging the throttle to a position causing the engine to idle; means including an impeller for providing an additional supply of air to that normally passing to the carburetor, and means associated with said throttle operating means for stopping the operation of said impeller incident to return of said throttle to said idling position.

32. In an air supply system for the internal combustion engine of a motor vehicle, including a carburetor, a throttle controlling the engine, and means for operating the throttle including means urging the throttle to a position causing the engine to idle; means including an impeller for providing an additional supply of air to that normally passing to the carburetor, an electric motor for operating said impeller, a switch for controlling said motor, and means operating upon release of said throttle operating means for operating said switch to shut off said motor.

FREDERICK M. LASERSON.
